UNITED STATES PATENT OFFICE.

GEORGE PATTERSON, OF MANCHESTER, NEW HAMPSHIRE, ASSIGNOR TO DRAPER COMPANY, OF HOPEDALE, MASSACHUSETTS, A CORPORATION OF MAINE.

WARP-STOP-MOTION ATTACHMENT.

1,078,215.

Specification of Letters Patent.

Patented Nov. 11, 1913.

Application filed April 14, 1913. Serial No. 760,884.

To all whom it may concern:

Be it known that I, GEORGE PATTERSON, a citizen of the United States, residing at Manchester, county of Hillsboro, and State of New Hampshire, have invented an Improvement in Warp-Stop-Motion Attachments, of which the following description, in connection with the accompanying drawings, is a specification, like letters on the drawings representing like parts.

The invention to be hereinafter described relates to looms, and more particularly to an attachment for warp stop motions, whereby the loom may be stopped through the warp stop motion even though the warp threads themselves may be in normal condition.

As well understood by those skilled in the art, it is frequently necessary for the loom tender or operative to give attention to parts at the back of the loom, as, for instance, in removing lint from about the drop wires or warp detectors, or in working upon other features; and occasion sometimes arises while the operative is thus engaged 25 to stop the loom quickly, without taking time to pass through the alley-ways to reach the shipper at the front of the loom.

With these facts in mind, the aims and purposes of the present invention are to 30 provide simple and convenient means, acting through parts of the warp stop motion, which will enable the operative to quickly stop the loom without the necessity of passing around the structure to reach the shipper, all of which will best be made clear 35 from the following description and accompanying drawings of one convenient form of means for carrying the invention into practical effect, it being understood, of course, 40 that the invention is not limited to such particular means, but is set forth in its true scope by the claims.

In the drawings: Figure 1 is a central vertical section from front to rear of sufficient 45 of a loom and warp stop motion to make clear the character and operation of the present invention; and Fig. 2 is an enlarged detail at the rear of the loom showing portions of the warp stop motion and 50 the association therewith of a device embodying a convenient form of the invention.

The loom may be of any well-known or desired character having a warp stop motion, and, as typified in the drawing, it com-

prises a frame 1, the usual lay 2, said parts 55 being operated as usual from any desired source of power. These parts, as well as the whip-roll or warp guide 6 need no further detailed description, as they are well-known and familiar to those skilled in the 60 art. Rising from the loom frame 1 are the brackets 7, one at each side of the loom, which serve as supports for a warp stop motion.

In the form of the invention illustrated, 65 the warp stop motion comprises a series of drop devices or warp detectors 8 which may be arranged in two transverse rows, as shown, each drop device or detector having a guiding slot 9 through which pass one 70 of the guide rods 10. Each drop device or detector has also an eye 11 for the passage of a warp thread 12, whereby, the drop devices or detectors are normally held out of the path of a vibrator or feeler 13 carried by a rock shaft 14 through the arms 15, Fig. 2. This vibrator or feeler 13 may be of usual character and be given its rocking or feeler movement by the rods 16 or other suitable means common in this class of 75 devices, the construction being such that should the feeler or vibrator be obstructed in its movement by a drop device or detector due to a broken or abnormally slack warp thread, the shipper 17 will be dislodged 80 from its holding notch, and the loom be brought to rest. As hereinbefore noted, the feeler, as well as the drop devices or detectors 8, and the means between the feeler and the shipper 17 for throwing the shipper 85 from its holding notch when the feeler movement is obstructed may be of any approved form and construction, and being well known and familiar to those skilled in the art further illustration and description 90 thereof will be unnecessary.

In the form of the device illustrated, see Fig. 2, the brackets 7 have secured thereto the depending brackets or arms 18 to which are secured by means of screws 20 or otherwise, the side bars or rails 19, 19 of the warp stop motion. The guide rods 10 which pass through the drop devices or detectors 8, may likewise be secured in guiding position on the depending brackets 18 by suitable 100 means, such as the bolts 21 passing into lugs 22 projecting from the brackets 8. While these details are found to be convenient form

of means for the purpose stated, it will be understood of course, that such details are not essential and may be varied.

In warp stop motions of this general character, where a vibrating feeler is employed, it is common when movement of the feeler 13 is obstructed to detach the shipper from its holding notch and cause loom stoppage, and the present invention takes advantage of this fact and provides means which may be conveniently operated by the loom tender, when at the rear of the loom or at points from which the shipper cannot be reached, to quickly act through the warp stop motion 15 to stop the loom. As one convenient form of means to this end, the present invention contemplates a finger normally inoperatively related to the warp stop motion, and which may be readily moved into operative relation 20 therewith and act therethrough to quickly stop the loom. One form of such finger is indicated by the drawings, wherein 23 is a rod extending through a bearing 24 of an arm 25 which may be secured in position and 25 to the loom frame by suitable means, such as the bolt 26 which serves to also secure the depending bracket 18 to the brackets 7, as indicated in Fig. 2. Obviously the arm 25 for the rod 23 may be otherwise secured in 30 position. At its upper end the rod 23 may be provided with a hand or finger-piece 27 and between it and the bearing 24 is a spring 28 which normally acts to hold the lower end of the rod 23 out of the path of the feeler 13, substantially as indicated in Fig. 2. The arm is preferably so located with respect to the warp stop motion, that the lower end of the rod 23 may extend downward about 35 centrally between the side bars or rails 19 so that upon depression thereof into the path of the vibrator, it will act quickly upon the vibrator to arrest it in either direction of its movement, but, while this is a good and convenient disposition and relation of the parts, 40 such relation may be varied within the true scope of the invention defined by the claims.

From the construction described, it will be noted that the rod 23, which for identification may be known as the manual stop finger, is disposed at the rear part of the loom in convenient position to be reached by the loom tender at the back or side of the loom, and that when manually operated, it projects into the path of and arrests the feeler, with 45 consequent quick stoppage of the loom, and when in normal position it is held out of the path of the feeler.

The device is simple, readily accessible at the back of the loom, and efficient under 50 manual operation; and while its form as

illustrated is a convenient embodiment of the invention, it may be varied.

What is claimed is:—

1. In a loom, the combination of a warp stop motion comprising a vibrating feeler, 65 and a manually operable finger projecting at the rear of the loom for engagement by the attendant and adapted to be moved into the path of and to arrest movement of the feeler.

2. In a loom, the combination of a warp stop motion comprising a vibrating feeler, a series of drop devices normally held out of the path of the feeler, and adapted to arrest movement of the feeler upon abnormal condition of a warp thread, and a finger projecting at the rear of the loom for manual operation by the attendant and adapted to arrest movement of the feeler during normal condition of the warp threads. 75

3. In a loom, the combination of a warp 80 stop motion, a finger extending at the rear of the loom in position to be engaged by the attendant and mounted for coöperation therewith, means for normally maintaining said finger in inoperative position and permitting it to be manually moved into operative position to stop the loom through the warp stop motion. 85

4. In a loom, the combination of a warp stop motion, a finger, means for supporting 90 the finger in position adjacent the warp stop motion, and in position to be engaged and operated by the loom tender, and a spring for holding the finger normally in inoperative position and permitting it to be moved 95 into operative position by the loom tender to cause the warp stop motion to operate to stop the loom.

5. In a loom, a warp stop motion comprising drop devices and a vibrating feeler for 100 stopping the loom on the occurrence of a warp fault, a manually operable finger extending from a point adjacent the warp stop motion for engagement by the attendant at the rear of the loom, a guide for directing 105 movement of the finger toward and from the path of the feeler, and means for normally maintaining the finger out of the path of the feeler and permitting it to be manually moved by the attendant at the rear of the loom into the path of the feeler to cause loom stoppage in the absence of a warp fault. 110

In testimony whereof, I have signed my name to this specification, in the presence of two subscribing witnesses.

GEORGE PATTERSON.
